LIFE PRESERVER JACKET

George Mikos, Washington, D. C., assignor of
one-fourth to William Chevie, Washington,
D. C.

Application March 31, 1938, Serial No. 199,227

4 Claims.

(Cl. 9—20)

The present invention pertains to life preserver jackets, and it contemplates the provision of an extremely simple and inexpensive device of the character set forth that is readily and easily adjusted to the person using the jacket and it is so constructed and arranged that it will support the wearer in an upright as well as a reclining position in the water regardless of the condition thereof.

10 The invention further contemplates a device of the character recited that permits the use of arms and legs of the wearer for the purpose of assisting in holding the wearer in either an upright or reclining position, and this without affecting in any manner the buoyancy of the jacket.

Another object of the invention is the provision of a jacket that may be put on with the least amount of effort and without prior experience in the adjustment thereof, and hence may be quickly and readily used in a sudden emergency; the device carrying these features because of the fact that it is of unitary construction, and hence no additional elements or devices are required as is the case with the usual life preserver devices.

Another object of the invention is the provision of means at the neck and bottom of the jacket for keeping the neck in an open and upright position, the bottom in an open uniform position.

Other objects of the invention will be fully understood from the following description and claims when the same are read in connection with the drawing accompanying and forming part of this specification in which:—

Figure 1 is a front elevational view of the life preserver jacket and illustrating the bottom and neck means, the arm rest elements and securing means therefor in full lines when the device is in operation, and in dotted lines when the device is in its inoperative position.

Figure 2 is a side elevational view of the jacket.

Figure 3 is a longitudinal sectional view taken 45 in the plane indicated by the line 3—3 of Figure 2 and looking in the direction of the arrows.

Similar numerals of reference designate corresponding parts in all of the views of the drawing.

50 Referring to the drawing my novel jacket comprises the body portion designated as a whole by the numeral 4 and the said body portion is preferably formed of canvas, however any other suitable water repellent material of rugged texture may be used as the purpose is to withstand

rough usage and act as a cushion or guard to the body of the wearer, should the wearer come in contact with debris or the like that may be injurious to the body, were the body not protected by such material. In addition, the canvas or other material would also tend to repel water or the like to a certain degree. The body portion is provided with a neck or collar 5, the arms 6, the collar having secured to the outside face a rubber fabric 5' that keeps the collar in an open 10 and upright position at all times, and at the lower end of the body of the jacket is provided a rubber fabric 4', the same assisting in a more or less snug fit about the hips of the wearer.

Arranged in the body portion 4 of the jacket 15 are pockets 7 provided with a flap 7', the flap being stitched or otherwise secured to the body 4 of the jacket as indicated by 8. Adapted to be stitched as indicated by 9' or otherwise secured in the pockets 7 are tubes or casings 9, 20 and the casings 9 are preferably adapted to enclose cores of cork or other buoyant material designated by 10. In addition, on the front and rear faces of the body portion 4, I provide the casings 11 and 12 that are adapted to confine 25 cork or other buoyant materials 13 and 14 between the outer faces of the front and rear of the jacket and the inner faces of the members 11 and 12. As clearly shown in Figure 1 the casing 12 is stitched or otherwise secured to the 30 body as indicated by the numeral 15 and manifestly this construction is repeated on the rear face of the body 4 of the casing 11.

Adapted to be hingedly secured at 16 and 17 to the body 4 are rests 18 and 19, the hinge members as illustrated comprising straps 16' and 17' that are secured around the rests and serve as a supporting means for the rests 18 and 19. The rests 18 and 19 are preferably filled with cork or other buoyant material. Also secured to the 40 rests 18 and 19 are hinged straps of canvas or other suitable material 20 and 21, and the strap 20 is provided with a snap hook 22 well known in the art, while the strap 21 is provided with a ring 23, such provision being made so that the occupant of the jacket may, when desirable snap the hook to the ring and thereby hold the arm rests in a position parallel with the sleeves of the jacket in order to float or rest the arms under certain conditions. In addition, a ring 24 is 50 provided at the point indicated, so that the straps may be secured to the body portion proper of the jacket and retaining the rests in the position as indicated in Figure 1 of the drawing.

Secured on the collar 5 of the jacket is a plu- 55

rality of rings 25 that are spaced equi-distantly around said collar and through these rings is a cord 26 that is adapted to permit the collar to assume a snug fit if desired. However I would 5 distinctly have it understood that operation of the jacket will be positive at all times either with the strings in their normal position or in their drawn position. The construction of rings 25 and draw string 26 is duplicated at 27 and 28 10 on the waist portion of the jacket 4.

I would have it distinctly understood that if the user of the device desires, it is not necessary to secure the straps 20 and 21 to each other but may disengage these straps when the same will 15 assume the dotted line position shown in Figure 1, and the rests 18 and 19 will drop to the position indicated by the dotted arc line. When in the water however, the rests 18 and 19 will assume the position shown by the solid lines in 20 Figure 1, and the disengaged straps by the dotted lines.

What I claim is:—

1. A life preserver jacket of unitary structure having elastic means at the top and bottom of said jacket, the elastic means at the top of the jacket forming a neck portion and holding said neck portion in an open and upright position, the elastic means at the bottom of the jacket holding the bottom in an open position, a single rectangular pocket on the front and rear of the jacket, buoyant material housed in each of said pockets, a plurality of horizontal tubular members provided with buoyant material on the front and rear of the jacket, the top and bottom portions of the jacket provided with a plurality of rings and a draw string whereby the neck and bottom portion of the jacket may be snugly drawn about the wearer of the jacket.

2. A life preserver jacket of unitary structure, arm and neck portions formed therein, elastic means holding the neck and bottom portion in open position, pockets each substantially co-extensive with the front and with the rear of the jacket respectively and each housing buoyant material, a plurality of cups secured to the front and rear of the jacket, casings adapted to house a buoyant material on the front and rear of the jacket, the ends of the casings adapted to engage 10 the cups for fixedly securing the casings to the jacket.

3. A life preserver adapted to be readily put on in an emergency including a jacket member open at the neck and waist whereby it may be 15 slipped on over the wearer's head, said jacket member having a neck portion of elastic material holding the neck portion open and a lower waist portion of elastic material holding the lower waist portion open, flexible buoyant members secured to and extending across the front and back of said jacket member.

4. A life preserver adapted to be readily put on in an emergency including a jacket member open at the neck and waist whereby it may be 25 slipped on over the wearer's head, said jacket member having a neck portion of elastic material holding the neck portion in an open position and a lower waist portion of elastic material holding the lower waist portion in open position, pockets substantially coextensive with the front and with the rear of the jacket, buoyant material housed in each, flexible buoyant members secured to and extending across the front and back of said jacket member.

GEORGE MIKOS.
